INCINERATOR

Hugo Edwin Carl Huber, London, England, assignor to The Nineteen Thirty Investment Trust Limited, London, England, a British company

Application December 2, 1947, Serial No. 789,313
In Great Britain January 1, 1947

4 Claims. (Cl. 219—35)

1

This invention relates to incinerators and is concerned with the provision of a self-contained unit for the satisfactory disposal of soiled sanitary towels, septic bandages, soiled dressings and the like hereinafter referred to as "bandages."

According to the present invention there is provided an incinerator for soiled bandages, comprising a combustion chamber and a flue disposed above such combustion chamber, wherein a hopper device is arranged to be angularly movable in a mouth through which soiled bandages are to be introduced into the combustion chamber, said hopper device being so arranged that it can be brought to a position where a soiled bandage can be placed in the hopper whilst the latter closes said mouth, the hopper device being then displaceable to a position where it discharges the bandage into the combustion space and where it also serves to close said mouth.

For a better understanding of the nature of the invention and to show how the same may be carried into effect reference will now be made to the accompanying drawings in which:

Figure 1 is a front elevation of an incinerator of the invention, the enclosing casing being removed,

Figure 2 is a side view of Figure 1 as seen from the left hand side of Figure 1,

Figure 3 is a sectional view taken on the line III—III of Figure 1 as seen in the direction of the arrows,

Figure 4 is a view similar to Figure 2 but showing a different operative position, and

Figure 5 is a view similar to Figure 3, showing the same operative position as in Figure 4.

In this example the incinerator essentially comprises a wall plate 1 to which two principal side plates 2 and 3 are secured. Two electrical resistance heating elements 4 and 5 are fixedly disposed in spaced relation between the side plates 2 and 3, so as to leave a combustion space between these heating elements. An asbestos sheet 7 is held in position loosely by a clip-on strip 8, and serves to prevent escape of heat from the combustion chamber. A curved plate 9 is located above the combustion chamber and is shaped so as to direct articles for incineration, into such chamber.

Plates 10 and 11 are arranged to constitute a flue, which is at its upper end closed by a further plate 12, associated with a chimney 13. As indicated at 14 (Figures 3 and 5), there may be asbestos lagging to prevent the undesired escape of heat from the flue. At its lower end the plate 11 is bent upwardly to form the upper wall 15

of a mouth, of which the lower wall is formed by the curved plate 9. The mouth is provided with a closure flap 16 pivotally supported at 17.

A reception device for articles to be incinerated 5 is carried upon a pivot 18, and is shaped as a hopper comprising two relatively angularly displaced plates 19 and 20. From a comparison of Figures 3 and 5 it will be seen that the hopper device can occupy a position where the plate 20 10 is in continuation of the flue formed over the combustion chamber, or alternatively the plate 19 can occupy this position. The angular control of the hopper device is obtained through its pivotal support 18 which carries a cam 19A co-operating with a pin 20A provided upon a bar 21. A bracket 22 pivotally receives one end of an operating handle 23 which is effectively integral with the bar 21. The latter possesses a further pin 24 for co-operation with a cam 25 secured 15 upon the pivot 17 of the closure flap 16.

In Figures 2 and 3 the incinerator is seen when the handle 23 is in a normal position of rest. The cam 19A is then held by a spring 26 in such position that the hopper device is located 20 as shown in Figure 3 i. e. with the plate 20 closing the mouth through which access to the combustion space or chamber 6 can be had. At the same time the closure flap 16 occupies the position shown in Figure 3 under the action of gravity. If now the operating handle 23 is swung towards the position shown in Figure 4, then first the pin 20A effectively encounters the cam 19A, and, against the action of the spring 26, causes the latter to be turned towards the position shown in Figure 4. This results in the swinging of the hopper device towards the position shown in Figure 5, where the plate 19 closes the mouth and completes the flue over the combustion space. After the swinging movement of the hopper device has commenced, the pin 24 encounters the cam 25 and causes the closure flap 16 to be raised to the position shown in Figures 4 and 5.

When the incinerator is in the operative position shown in Figures 4 and 5, a soiled bandage can be dropped into the hopper device and it will rest upon the plates 9 and 19. When the handle 23 is returned to the position shown in Figures 2 and 3, the hopper device swings to displace the bandage into the combustion chamber, the plate 20 finally resuming its location where it continues the flue, so that fumes from the combustion process will not escape from the entry mouth. It is important to realise that if the handle 23 is operated whilst a bandage is already being incin-

erated, then the plate 19 of the hopper device will serve to close off the mouth and prevent the undesired escape of fumes.

The swinging movement of the bar 21 is employed to control electrically the operation of the resistance heating elements 4 and 5. These elements have their circuit interrupted and completed through a time-delay mercury switch. The mercury switch comprises a tube 30 having contacts 31 and 32 which can be bridged by the mercury within the tube 30. The tube is supported upon an arm 33 which is pivoted at 34 to the bracket 22. The lower end of the arm 33 has a plunger 35 secured to it, the plunger co-operating with a dash-pot 36. A set-screw 37 is located on a lug 37A provided upon the bar 21 and is adapted to engage the arm 33. When the handle 23 is in the position shown in Figures 2 and 3, the bar 21 lies with the set-screw 37 remote from the arm 33. The mercury within the tube 30 does not bridge the contacts 31 and 32, and therefore the heating elements 4 and 5 are de-energised. If now the handle 23 is swung towards the operative position shown in Figures 4 and 5, the bar 21 turns until the set-screw 37 contacts the lower depending portion of the arm 33. The plunger 35 is forced into the dash-pot 36, and the arm 33 swings so that the mercury within the tube 30 bridges the contacts 31 and 32 (i. e. the position shown in Figure 4). The heating elements 4 and 5 are now supplied with electric power and an intensive heat develops in the combustion chamber. When the handle 23 is allowed to return to the inoperative position shown in Figures 2 and 3, the plunger 35 gradually moves out of the dash-pot 36, at a pre-determined rate that can be set by adjustment of the dash-pot and plunger device. Preferably the dash-pot and plunger device is of the known kind in which the initial outward movement of the plunger 35 is relatively slow whilst the last part of such movement, is rapid. The rapid movement accounts for the critical swinging of the tube 30 to the position where the mercury no longer bridges the contacts 31 and 32. It is of course desirable that the break in the electrical circuit should be rapidly achieved so as to reduce sparking within the mercury switch.

As indicated in Figure 1, there is a lamp holder 38 which is intended to receive a pilot lamp so that when the circuit to the heating elements 4 and 5 is completed, the pilot lamp glows and indicates this condition.

The combustion chamber 6 is lined with several parallel wires one of which may be seen at 39 in Figures 3 and 5. The wires are spaced from one another so that effectively at their lower sides they form a grate upon which the bandage to be burnt may rest. As seen from below the grate has a convexity in order to permit a scraper plate 40 to swing therebeneath. The plate 40 is carried by a pair of sector arms 41, each arm being pivotally secured to a bracket 42. A spring 44 ensures that the scraper plate assembly normally occupies the position shown in Figures 2 and 3, the travel of the assembly being limited by a fixed stop 47. One of the sector arms 41 carries an angle bracket 45 engaged by a pin 46 provided upon the bar 21. As seen best from Figures 2 and 4, when the handle 23 is brought to the operative position (Figure 4) the pin 46 causes the scraper plate assembly to be displaced from the position seen clearly in Figure 3 to that in Figure 5. The scraper plate 40 ensures thus that the grate of the combustion chamber is peri-

odically scraped clear of ashes. The plate 40 is preferably made wholly perforate so that ashes can pass through the same when they fall through the grate of the combustion space. A tray 50 is provided for the reception of the ashes, this tray being supported by a bar 51 held by wing-nuts 52 to angle-pieces 53, fixed to the brackets 42. Corner-pieces 54 are attached to the ends of the brackets 42 and receive the upper front corners of the tray 50. By slackening off the wing nuts 52, the bar 51 can be withdrawn by grasping a depending hand grip portion 51A.

The finished incinerator has an enclosing casing which is not shown in the drawings. The 15 casing is provided with a door which lifts with the closure flap 16, and there is, of course, a window to permit viewing of the lamp held in the lamp-holder 38. A suitable slot is formed in the casing to permit the handle 23 to project therethrough.

The casing preferably is designed so as to leave an air gap around the enclosed incinerator, thus to afford a heat insulation for the casing.

I claim:

25 1. An incinerator comprising a combustion chamber having a stationary grate at its lower end and a flue at its upper end, electric heating means for heating said combustion chamber, a switch for controlling the supply of current to said heating means, a time delay device operatively connected with said switch to assure the closed switch position for an adjustably predetermined period of time after the switch has been closed, an incinerator charge receiving opening in said flue, a closure member for said opening, said closure member being movable from an open charge receiving position to a closed charge discharging position, a movable ash scraper associated with said grate, a single hand operated control means for simultaneously moving said closure member and said ash scraper, and means connecting said control means with said switch means whereby the movement of said control means to effect a closure of said closure member is also effective to move said switch to a closed position for energizing said heating means.

2. The incinerator as claimed in claim 1 wherein said closure member consists of two plates effectively joined along one side and angularly displaced with respect to one another about their line of joinder, said closure member being pivotally connected to said flue at the axis of joinder of the plates so that the flue opening is closed by one of said plates when the closure is in the open position to receive a charge between said plates, the movement of said closure to the closed position being effective to discharge the charge into said combustion chamber with the other of said plates in position to close the opening in said flue.

3. The incinerator as claimed in claim 2 wherein a cover member is pivotally connected to said flue in a manner to overlie said opening and closure member when said closure member is in the closed position, and means operated by said single control means for moving said cover means to expose said opening and closure member when said closure member is moved to the charge receiving open position.

4. The incinerator as claimed in claim 1 wherein said ash scraper comprises a scraper plate carried by pivotal arms beneath said grate, said arms being operatively connected with said single control means whereby each movement of said control means causes a pivotal movement of said

75

arms to effect a traversing of the grate by said scraper plate in a manner to remove ashes from said grate.
